UNITED STATES PATENT OFFICE.

ANTON WITEK, OF NEW YORK, N. Y.

WINDOW-CHAIR.

SPECIFICATION forming part of Letters Patent No. 367,259, dated July 26, 1887.

Application filed February 23, 1887. Serial No. 228,463. (No model.)

To all whom it may concern:

Be it known that I, ANTON WITEK, a citizen of Austria, residing at New York, in the county and State of New York, have invented 5 a new and Improved Window-Chair, of which the following is a specification.

This invention relates to a window-chair, upon which a person may stand to wash the outer side of a window, and which may be securely clamped to the wall. When the chair is not in use, it may be folded together to occupy but little space.

The invention consists in the various features of improvement hereinafter more fully 15 pointed out.

In the accompanying drawings, Figure 1 is a vertical longitudinal central section of my improved window-chair. Fig. 2 is a top view thereof.

20 The letter W represents the wall of a building, and V the window-frame. Upon the horizontal portion of this frame there is placed the improved window-chair, consisting, essentially, of a pair of clamping jaws or legs pivoted to a platform. This platform is composed of side rails, a, connected in front by a cross-piece, b, having projecting shoulders b', and at the rear by a cross-piece, d, which serves to support the person who is to occupy the 25 chair. The forward leg or clamping-jaw, c, is hinged to the cross-pieces a by pivots c', and abuts against the stops b', which prevent such jaw from receding from the wall W and keep the jaw down at right angles, as shown. The 30 rear jaw consists of two rods, w, pivoted at w' to cross-piece, a, and joined at the center by a cross-bar, w², and at the lower end by a clamp-plate, w³, placed at an oblique angle to rods w. The rear jaw is pivoted to the rear end of the 35 platform, so that it may be inclined toward the wall.

By swinging the rear jaw upon its pivots it is evident that the plate w³ may be pressed against the wall W, and by locking the rear 40 plate in position the entire chair will be locked to the wall. In order to lock the rear jaw, I

secure to it one end of a chain, s, the links of which may be slipped over a hook, s'. By drawing the chain taut and then slipping the chain-link over the hook the clamp-plate will 50 be properly locked against the wall.

To afford an additional security, especially against breaking of the chain s, I cut into one or both of the rods w a rack, as shown at r, which is engaged by a pawl, p, pivoted to lugs q 55 of rails a. This pawl is connected to a hand rod or chain, v, which can be locked to a button, x. After the jaw has been swung in position the pawl is swung up to engage the rack, and then the chain v is locked to the button x. 60 Thus a double security is obtained against accidents. Upon the platform there is mounted a frame that may be folded, if desired, and which is to prevent the occupant from falling from the platform. This frame consists of two 65 rear uprights, f, and two front shorter uprights, e, pivoted, respectively, at f' and e' to side rails, a. The two uprights are joined by cross-pieces n and n', and are provided with the arms h and k, pivoted, respectively, at h' 70 and k'. The arms h and k are perforated or slotted at their free ends, to be slipped over a stud or pin, m, on uprights e. Thus the entire frame is self-supporting. To fold the frame together, the arms h k are released from studs 75 m and folded down, and then all of the four uprights may be folded upon the platform.

What I claim is—

The combination of a horizontal platform having front jaw, c, with a rear jaw composed 80 of arms w w, pivoted to the rear end of the platform and carrying an oblique clamp-plate, w³, one of the rods w having a rack, r, and with the pawl p, and with chains and hooks for holding the rear jaw against the wall and 85 the pawl against the rack, substantially as specified.

ANTON WITEK.
